UNITED STATES PATENT OFFICE.

ADOLPH ROSNER, OF BRIDGEPORT, CONNECTICUT, ASSIGNEE TO THE LOCOMOBILE COMPANY OF AMERICA, OF NEW YORK, N. Y., A CORPORATION OF WEST VIRGINIA.

VALVE.

1,246,787.

Specification of Letters Patent. Patented Nov. 13, 1917.

Application filed August 23, 1916. Serial No. 116,540.

To all whom it may concern:

Be it known that I, ADOLPH ROSNER, a citizen of the United States, and a resident of Bridgeport, in the county of Fairfield and State of Connecticut, have invented an Improvement in Valves, of which the following description, in connection with the accompanying drawings, is a specification, like characters on the drawings representing like parts.

This invention relates to valve mechanisms, and is more especially concerned with a puppet valve mechanism particularly adapted for use in engines of the internal combustion type, in which the valves are actuated by tappets which, heretofore, have been more or less noisy in action owing to the striking of the valve tappets or lifters against the valve stems.

My invention will be best understood by reference to the following description, when taken in connection with the accompanying drawings showing three specific embodiments thereof, while its scope will be more particularly pointed out in the appended claims.

In the drawings:

Figure 1 is a vertical sectional view of a portion of an internal combustion engine equipped with a valve mechanism embodying my invention;

Fig. 2 is an enlarged, detail vertical section of one form of valve embodying my invention;

Fig. 3 is a similar section of a second form of valve embodying my invention; and

Fig. 4 is a similar section of a third form of valve embodying my invention.

Referring to the drawings, and more especially now to Fig. 1, I have there shown a valve mechanism embodying my invention, the general characteristics of the mechanism being similar to those commonly employed in well known internal combustion engines.

In the illustrative mechanism, 5 is the cylinder, 6 the combustion chamber, and 7 an intake or exhaust passage. Communication between the chamber 6 and passage 7 is controlled by a puppet valve 8 coöperating with a valve seat 9. The valve, which will be more fully described hereinafter, is provided with a head 10 and a stem 11, the latter working in a valve stem guide 12, encircling which is a helically coiled spring 13, one end of which abuts against the cylinder casting,

and the other against a collar 14, which is held in fixed position on the stem by means of a key 15 in a well known manner. The spring 13 normally holds the valve seated, and restores it to its closed position, after it has been lifted by the actuating mechanism which I will now describe.

Disposed in axial alinement with, and engaging the lower end of the valve stem 11, is a valve tappet or push rod 16 mounted to slide in a push-rod guide 17, and carrying at its lower end a roller 18 engaging a cam 19 on a cam-shaft 20. Rotation of the latter causes the valve lifter or push rod to be lifted at the proper time in the operation of the engine, as is well understood.

Heretofore, it has been customary to provide a clearance between the valve lifter or push rod and the valve stem, such clearance being in practice approximately five-thousandths of an inch. A clearance of this sort has been necessary in order to permit the valves to be seated tightly under the influence of their springs and thereby prevent leakage. This clearance, however, is objectionable because of the noise produced by the hammer action of the valve lifters, or push rods, against the valve stems, and it is a matter involving great skill and delicacy of adjustment so to adjust the tappets as to insure tight closing of the valves, yet with as quiet an action as possible. I am able to eliminate these disadvantages by the use of the novel valve in its various forms, which I will now describe.

Referring to Fig. 2, I have there shown in detail the valve illustrated in Fig. 1. In order to permit the valve stem to continue to move toward the valve lifter or push rod after the seating portion of the valve has seated upon its seat 9, the valve, as a whole, comprises a suitable yielding part interposed between the seating portion and the actuating means. This yielding part may take various forms, and may be variously located, but herein the head is made elastic so that the valve is resiliently extensible in the direction of its travel. By this means, the valve stem, under the influence of the spring 13, can follow the valve lifter after the seating portion of the valve has come to rest upon its seat, and therefore uninterrupted connection is maintained between the valve and the valve actuating means.

In the form shown in Fig. 2, the resilient

head comprises a plurality of laminations 21, 22, 23, 24, 25 and 26. These laminations may be, and preferably are, made of tungsten steel, which has the necessary properties to enable it to resist for a long time the tendency to pit and warp through the action of the intense heat to which it is exposed. The stem 11, however, may, and preferably is, formed of a different and less expensive grade of steel, usually a soft carbon grade. It will be understood, however, that the character of the metals of which the valve is composed is not essential to my present invention.

15 The valve head, made up as it is of several laminations of metal disposed in planes substantially at right angles to the longitudinal median line of the stem, is elastic to such an extent that, after it is seated, it will 20 flex and allow the stem to be drawn to a further extent by the spring, and thus maintain contact of the valve stem with its lifter after the valve has become seated.

The laminations may be secured to the 25 stem 11 in any suitable manner, but herein the latter is provided with a shouldered neck 27 to receive the laminations which are centrally perforated for that purpose. The laminations may be secured to the neck in 30 any suitable manner, as by heading over the neck at 28, and thus confining the laminations between two shoulders 29 and 30. One of the laminations may be wrapped about the circumferential edges of another, or 35 others, and in the form shown in Fig. 3, the lamination 25 is provided with a circumferential flange or lip 31, having a generally frusto-conical form to fit the circumferential edges of the laminations 21, 22, 23 40 and 24, which are similarly shaped. The lamination 23, however, is of comparatively small diameter, and thus there is permitted a greater freedom of action or elasticity adjacent the perimeter of the valve than near 45 its center.

In the form shown in Fig. 3, the valve head 10^a is composed of laminations 21^a, 22^a, 23^a, 24^a, 25^a and 26^a, secured as before to the neck 27^a. In this form, however, it has the 50 lamination 21^a, which is extended and is provided with a frusto-conical flange overlapping the edges of the laminations 22^a, 23^a and 24^a.

In the form shown in Fig. 4, the valve 55 head, which is designated 10^b, is made up of laminations 21^b, 22^b, 23^b, 24^b, 25^b and 26^b, and the construction is similar to forms shown in Figs. 2 and 3, except that the flange described in connection with these 60 forms is omitted.

In each of the described forms, there is the desired flexibility of action which permits the valve to yield and its stem to follow and remain at all times in engagement with

the valve lifter, so that no tapping sound is 65 heard. By this means, an exceedingly quiet running engine is produced, without danger of the valves leaking. The flexible head has the further advantage of accommodating itself to the seat, and thus assuring 70 a snug fit at all points, in spite of slight irregularities which would otherwise necessitate regrounding of the valve to prevent leakage. This, in itself, is a distinct and 75 valuable advantage.

While I have herein shown and described three specific embodiments of my invention for illustrative purposes, and have disclosed and discussed in detail the construction and arrangement incidental to three specific applications thereof, it is to be understood that the invention is limited neither to the mere details or relative arrangements of parts, nor to the specific embodiments herein shown, but that extensive deviations from 80 the illustrated forms or embodiments of the invention may be made, without departing from the principles thereof.

Having thus described my invention, what I claim and desire by Letters Patent to 85 procure is:

1. In an engine, the combination of a cylinder having a chamber, valve actuating means, a valve seat, and valve means having a seating portion co-operating with said seat 90 and opening inwardly with relation to said chamber, and a yielding portion operatively interposed between said seating portion and said actuating means, whereby a portion of said valve means can continue to move toward 95 said actuating means after said seating portion has seated upon said seat.

2. In an engine, the combination of a cylinder having a chamber, valve actuating means, a valve seat, and valve means co-operating with said seat and opening inwardly 100 with relation to said chamber, and having a portion which is extensible in the direction of the valve's travel.

3. In an engine, the combination of a cylinder having a chamber, valve actuating means, a valve seat, and valve means co-operating with said seat and opening inwardly 105 with relation to said chamber, and having a portion which is elastic in the direction 110 of the valve's travel.

4. In an engine, the combination of a cylinder having a chamber, valve actuating means, a valve seat, and valve means co-operating with said seat and opening inwardly 115 with relation to said chamber, and having incorporated therein a resilient portion between its seating portion and said actuating means, whereby a portion of said valve means can follow said actuating means after 120 said seating portion has seated upon said seat.

5. In an engine, the combination of a cyl-

- inder having a chamber, a valve seat, valve unseating means, valve seating means, and valve means opening inwardly with relation to said chamber and including an elastic portion adapted to yield under the influence of said valve seating means and to maintain uninterrupted connection between said valve means and said valve unseating means.
6. In an engine, the combination of a cylinder having a chamber, a valve seat, a valve unseating means, valve seating means including a spring, and valve means opening inwardly with relation to said chamber and including an elastic part adapted to yield under the influence of said valve seating means and to maintain uninterrupted connection between said valve means and said valve unseating means.
7. In a valve mechanism, the combination of a valve seat, positively acting valve unseating means having a tappet, valve seating means including a spring acting in opposition to said tappet, and valve means including an elastic part adapted to yield under the influence of said valve seating means and to maintain uninterrupted engagement between said valve means and said tappet when the valve is seated.
8. In an engine, the combination of a cylinder having a chamber, a valve seat, a valve movable into and out of contact with said valve seat and having capacity for flexing in the direction of its travel with relation to said seat, and means for unseating said valve and for seating and flexing said valve as it seats.
9. In a valve mechanism, the combination of a valve seat, a puppet valve coöperating with said valve seat, said valve comprising a stem and a head, the latter being flexible in the direction of its travel, a valve tappet engaging said valve stem, means for actuating said valve tappet to cause the latter to coöperate with said valve stem to unseat said valve, and a spring acting in opposition to said valve tappet and adapted to flex said valve head and to coöperate therewith to maintain engagement of said valve stem with said valve tappet.
10. In a valve structure, the combination with a valve seat, of a puppet valve having a stem and a head, the latter comprising a plurality of laminations one of which is wrapped about the circumferential edges of another or others.
11. In a valve structure, the combination with a valve seat, of a puppet valve having a stem and a head, the latter comprising a plurality of laminations one of which is provided with a frusto-conical flange overlapping the edges of another or others.
12. In a valve structure, the combination with a valve seat, of a puppet valve having a stem provided with a shouldered neck, and a head comprising a plurality of centrally perforated laminations encircling and secured to said neck, the latter being headed over to secure said laminations thereto.
13. In a valve mechanism, the combination of valve actuating means, a valve seat 70, and the valve 8 provided with the flexible head 10.
14. In an internal combustion engine, the combination of a cylinder having a combustion chamber, a gas passage, a valve seat 75 having an opening to afford communication between said chamber and said passage, a puppet valve coöperating with said valve seat and opening in an inward direction with relation to said chamber, said valve comprising a stem and a head, the latter being flexible in the direction of its travel, a valve tappet engaging said valve stem, means for actuating said valve tappet to cause the latter to coöperate with said valve 85 stem to unseat said valve, and a spring acting in opposition to said valve tappet and adapted to seat said valve in an outward direction, to flex said valve head and to coöperate therewith to maintain engagement of 90 said valve stem with said valve tappet.

In testimony whereof, I have signed my name to this specification.

ADOLPH ROSNER.
